UNITED STATES PATENT OFFICE.

CLARENCE W. MONTAGUE, OF DENVER, COLORADO.

CLAY-POT-FINISHING MACHINE.

1,275,187.

Specification of Letters Patent.

Patented Aug. 6, 1918.

Application filed October 29, 1917. Serial No. 199,219.

To all whom it may concern:

Be it known that I, CLARENCE W. MONTAGUE, a citizen of the United States, residing at 857 Bryant street, in the city and county of Denver and State of Colorado, have invented a new and useful Clay-Pot-Finishing Machine, of which the following is a specification.

My invention relates to an improved device for rapidly and safely rotating (for the purpose of finishing) unburnt clay flower pots and the like while the same are "nested" together bottom upward in numbers or bunches sufficiently large to make a conveniently carrying load for the operator. The object of my invention is to eliminate the tedious and laborious task usually performed of handling each pot separately for the purpose of finishing or removing the rough edges left at or near the top by the machine or mold in which the pot was made.

My invention will be readily understood by reference to the accompanying drawings forming a part of this application, and in which:—

Figure 1 is an oblique projection of the machine showing all parts in their places as when in use. Fig. 2 is an orthographic projection of the removable sustaining rod extending through a partly finished bunch of flower pots (S and S') showing plan and elevation of the same. Fig. 3 is an orthographic projection of the removable turntable showing plan and elevation thereof. Fig. 4 is an elevation of the perpendicular shaft showing the nature of the vertical clutch used. Like reference characters designate corresponding parts throughout the drawings.

This machine, for the purpose of description, may be divided into three parts. The upper part; the lower part and the middle or connecting part.

The upper part of this machine consists of a continuously running perpendicular shaft, (k) (with pulley (o) collar (n) hanger and bearings (m) necessary for operating the same) in the lower end of which is constructed the upper part of a vertical clutch (L Fig. 4).

The lower part of this machine consists of a rising and falling carriage, (g) (with apparatus for operating the same) on the top center of which is constructed a removable turntable (a), which revolves in bearing (c).

The middle or connecting part of this

machine consists of a removable sustaining rod (b) or set of such rods to be used one at a time, on the top end of which is the lower part of the vertical clutch (L') to fit and work in conjunction with the part of the clutch (L) in the shaft above; the lower end of said rod being an angular taper fitted into a corresponding slot in the center of the turntable (a) below.

A device of this character being provided, the operation of the same is as follows:

The operator places his foot on treadle (e), which by means of connection (f) pulls down the carriage (g) with turntable (a) and sustaining rod (b), said carriage sliding up and down in guides (d) which are bolted to frame (p). The sustaining rod (b) is then removed and pushed through the drainage holes of a bunch of flower pots (s) as shown in Fig. 2. The lower end of the sustaining rod (b) with the flower pots (s) thereon is placed in the angular slot in the center of the turntable (a), the rod held in a vertical position and the flower pots being slid down on the rod till they rest securely on the shoulder provided on the turntable (a).

The operator then removing his foot from treadle (e) the carriage (g) together with turntable (a), sustaining rod (b) and bunch of flower pots (s) is immediately raised by means of weights (w) attached to sash cords (i) running over pulleys (h) until the lower part of the vertical clutch (L') has united with the upper part of the same (L) in the running shaft (k) above. This action causes the sustaining rod (b), the turntable (a) and the bunch of pots (s) to rapidly revolve. It is then only necessary to touch each pot separately with a piece of corset steel folded into a loop, or with any other suitable tool to smoothly and handsomely finish each pot in the fractional part of a second; or, if a less perfect finish will suffice, by holding thereon a long scraper or large piece of ordinary fly screen or other suitable tool the entire bunch may be finished in the fractional part of a second. The operator then placing his foot as before on treadle (e), the rod and turntable with the pots thereon instantly stop revolving. The pots are then removed and the operation repeated.

Having thus described my invention and its use, what I claim as new and desire to secure by Letters Patent is:

1. A machine for handling ware compris-

- 2
- ing a rotary member and a rod, one of whose ends is supported by the rotary member, whereby one of these members may be rotated through the medium of the other.
5. A machine for use in finishing ware comprising a rotary member, a sustaining member separate from the rotary member, extending therebeyond and adapted to pass through the ware and engage the rotary member, and means to rotate one of these members.
3. A machine for use in finishing unburned potter's ware comprising a turntable, a plurality of shoulders on the turntable to support ware of different diameters, a vertical removable sustaining rod adapted to pass through the ware and have the lower end seat in the turntable and rotate therewith, and means to engage and rotate the other end of the rod.
4. A machine for use in finishing unburned potter's ware comprising a horizontal turntable adapted to support the ware, a vertically reciprocable mounting for said turntable, a removable sustaining rod adapted to pass through the ware and extend vertically with its lower end seated in the turntable to rotate therewith, a clutch member on the upper end of the rod, and a companion clutch member mounted above the turntable and rod and adapted to engage the clutch member of the rod, and means to rotate said companion clutch member.
5. A machine for use in finishing unburned flower pots and the like comprising a horizontal turntable adapted to support the pots, a removable sustaining rod adapted to extend through the drainage holes of a bunch of nested pots and have its lower end seat in the turntable to rotate therewith, and means to rotate the rod and turntable.
6. A machine for use in finishing ware comprising a rotary member adapted to support the ware, a vertically reciprocable mounting for said rotary member, a vertical rod member extending beyond the rotary member and adapted to extend through the ware, and means to rotate one of said members.
7. A machine for use in finishing unburned flower pots and the like comprising a horizontal rotary member adapted to support the pots, a sustaining member separate from the rotary member, extending therebeyond and adapted to pass through the drainage holes of a bunch of nested pots supported on the rotary member and means to rotate one of these members.

In testimony whereof I have signed my name to this specification in the presence of two subscribing witnesses.

CLARENCE W. MONTAGUE.
